HIGH FREQUENCY PRESS FOR GLUEING SECTIONS OF WOOD TO PRODUCE PANELS, FRAMES AND OTHER TYPES OF GLUED WOOD STRUCTURES

Ernest E. Rosenquist, North Wilkesboro, N.C., assignor to L&L Machine Division, Modern Globe, Inc.

Filed Feb. 12, 1973, Ser. No. 331,958

Term of patent 14 years

Int. Cl. D15—09

U.S. Cl. D63—1

FIG. 2

FIG. 3

FIG. 4

FIG. 5

FIG. 6

FIG. 1 is a perspective view, with the top open, taken from the front and one side of a high frequency press for glueing sections of wood to produce panels, frames and other types of glued wood structures embodying my design;

FIG. 2 is a front elevational view of the high frequency press for glueing sections of wood to produce panels, frames and other types of glued wood structures;

FIG. 3 is a top plan view of the high frequency press;

FIG. 4 is a rear elevational view of the high frequency press;

FIG. 5 is an end elevational view of the press taken from the left side of FIG. 2; and

FIG. 6 is an end elevational view of the press taken from the right side of FIG. 2.

I claim:

The ornamental design for a high frequency press for glueing sections of wood to produce panels, frames and other types of glued wood structures, as shown.
